DECALCOMANIA KIT FOR MAKING MODELS OF AEROPLANES AND THE LIKE

Galen Papadakis, 20 Vista Lane, Levittown, N.Y.

Filed Dec. 4, 1957, Ser. No. 700,597

1 Claim. (Cl. 46—17)

This invention relates to the art of applying fitted or formed decalcomanias or so-called decals to various precut or constructed surfaces of model airplanes, ships, trains, cars, etc.

The decals in order to simulate a finished painted appearance are complete with numerals, insignia, glass panes or any other noticeable effect or detail that will aid in making a faithful replica of the model, when the decal or decals have been placed on the surface of the model being decorated.

A large number of hobbyists are concerned with the making of faithful replicas of various airplanes, ships, vehicles, etc. A considerable amount of detail goes into the making of these replicas, and it is of prime importance that the completed model be an exact duplicate, except for its size, of the full size airplane or other object of which it is intended to be a copy.

This has, of course, presented certain practical difficulties, particularly with respect to the decorated model. For example, a model of a full size airplane must carry the plane markings, in respect to the numerals, insignia, etc. This requires very close and exact work, and, of course, the failure to do a skilled job of lettering or drawing detracts measurably from the finished appearance.

In view of this, it is proposed in carrying out the present invention to provide decals, applicable to the surfaces of the model, which decals will carry the various pictorial representations, insignia, numbers, etc., that are to appear on the finished model. In this way, one will be enabled to produce a life-like simulation of the full size object, without the necessity of using up an excessive amount of time, effort, and without the further necessity of having an exceptionally high degree of skill in lettering, drawing and painting.

It is also proposed to provide a fitted decal for each of the various parts of the model being decorated. The decal is of one-piece construction and completely covers the formed part. Upon this surface of the decal is shown the necessary basic color of the model and upon this same surface of the decal there is included the necessary numerals, insignia or any other effect of detail that is necessary for that particular part of the model being decorated.

It is further proposed to provide decals which may be superimposed one upon another, so that a bottom decal may produce one type of marking, with a decal being then placed upon the bottom one so as to superimpose upon the first marking a second marking, to add even further to the life-like simulation of the full size object by the model.

Another object is to provide decals of the type described that can be so numbered and marked as to facilitate the use of each decal and its proper, assigned location upon the model.

A further object is to cause the identifying markings of the decals to also serve as aligning means for assuring that the decal will be properly placed in respect to the

2

model and in respect to other decals with which it is to be laminated.

Still another object of importance is to provide fitted decals for airplane or ship models, or for other types of models, which can be swiftly and easily applied, can be cut from a single large sheet to reduce costs, and can be manufactured in quantity to make the same commercially feasible in model kits.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a model airplane in its completed form, to which has been applied decals according to the present invention.

Fig. 2 is a fragmentary, exploded perspective view of the tail portion of the fuselage and of one of the decals.

Fig. 3 is an exploded, fragmentary perspective view of the model showing one of the wing tips and the associated decals.

Fig. 4 is a plan view of a modified form of decal.

Fig. 5 is a plan view of a second modified decal, a portion being broken away.

Fig. 6 is a fragmentary, plan view of one of the wing tips, on a model to be used with the decals of Figs. 4 and 5.

Fig. 7 is a plan view of a pair of small cover portions to be used to conceal the identifying and aligning markings in the completed model.

Fig. 8 is an exploded perspective view of a wing of a model airplane with an associated decal embodying another modified form of the invention.

Fig. 9 is a top plan view of the tip of a wing of a model airplane with a decal embodying still another modified form of the invention applied thereto.

Fig. 10 is a fragmentary plan view of a sheet from which the decals can be cut.

Fig. 11 is a fragmentary plan view of a kit showing the sheet of Fig. 10 in folded condition therein.

Fig. 12 is a plan view of another modified sheet from which various decals may be cut.

Referring to the drawings in detail, designated by the reference numeral 10 is a model airplane, having the fuselage 12, upper and lower wings 14, 16, wheels 18, propeller 20, rudder 22, and elevators 24.

The illustrated model is a model of a biplane of World War I vintage. Of course, the model could have any form, and might be a ship, automobile, train, car, etc.

In any event, when the model has been completely assembled, or for that matter prior to its final assembly, whichever is desired by the model maker, one finishes the exterior surfaces thereof through the use of decals. Paint can be eliminated completely, and, for example, the entire fuselage, if it is to be of a particular base color, could have one or more decals applied thereto.

For example, there could be decals applied to the side walls of the fuselage 12, another decal to the top wall, and a fourth decal to the bottom wall. These decals would be of a length, configuration, and breadth exactly matching that of the walls, and thus when applied would eliminate completely the necessity of painting of the body. This is considered sufficiently obvious as not to require special illustration. Finally, after the base color has been imparted to the fuselage in the manner described, additional decals can be employed, for the

purpose of producing upon the surface of the fuselage the desired insignia, numbers, or markings. Thus, a decal 26 can be applied to the side surface of the fuselage, and

would bear numerical indicia 28, in a typical arrangement.

Additional decals may be provided upon the various surfaces of the rudder 22 and elevators 24. Said decals could have rib lines showing therethrough, and could be provided with the numerical markings desired.

Thus, on the wings there could be decals, such as shown at 30. The entire surface of each wing may be covered with a single decal, having rib markings 32, simulating a fabric-covered wing or airfoil, of the type used in the airplane that is being duplicated.

After the decal 30 has been applied, decals 34, having wing insignias 36, may be applied directly over the decal 30, so as to provide the simulation of the insignia 36 being painted directly upon the ribbed, fabric-covered surfaces of the airplane.

To identify and to guide the decals to the locations at which they are to be used, the wing 14, decal 30, and decals 34 may all have a common identifying numeral as shown at 38, as for example the numeral "1".

It will be seen that the idea of the decals can be carried out throughout the entire visible surfaces of the model, eliminating painting completely, with all the decals being cut to a particular shape so as to be properly located in respect to the surfaces which they overlie. The final result is a highly attractive, exceedingly faithful replica of the full size object, with the model being completed without the necessity of laborious painting of the body and of the various insignia, numerals, etc.

In Figs. 4-6 there is shown a modification which is identical to the first form, with the exception that the guiding and identifying numerals are employed not only for the purpose of relating appropriate portions of the model body and appropriate decals to one another, but also for the purpose of properly aligning all the various parts with each other. For example, decal 40 having insignia 42 has at its opposite corners small identifying and aligning indicia 44. Decal 46 corresponds to decal 30 of the first form, having rib markings 48. Decal 46 has spaced identifying and aligning numerals 50. The wing 52 of the model has spaced aligning and identifying numerals 54.

In use, decal 46 is placed upon the wing 52, and is readily and accurately located by exact registration of the numerals 50 with the numerals 54. Not only can the decal 46 be identified in relation to the particular part of the model on which it is to be used, but also, the identifying means serves to properly position the decal.

Thereafter, the decal 40 which overlies decal 46, is applied by exactly registering the numerals 44 with the numerals 50.

It will be apparent that the arrangement has a highly desirable result of exact location of the decals, as well as relating all of a particular set of decals to each other and to the model body.

Thereafter, in order to conceal the numerals 44, small opaque dots or discs 56, constituting decal portions, are applied over the numerals 44, and have a color matching that of the adjacent, surrounding surface of the model.

In Fig. 8, a wing structure 58 of a model monoplane is shown of substantially rectangular shape with rounded ends and a central cut-away portion 60 for fitting the wing on a portion of the fuselage of the airplane. The decal 62 is of one-piece construction and is of similar shape, being provided with various insignia 64 on its surface.

Fig. 9 illustrates a fragment of a wing structure 66, with a decal 68 applied to a portion thereof. Markings 70 simulating the effect of a motor, and an identifying numeral indicated at 74 are provided on the surface of the decal, such surface preferably being colored, for example, red.

In Fig. 10 there is shown a fragmentary portion of a decal sheet, which sheet is provided with dash markings along which the decals are cut to separate the same one from another. For example, the sheet 76 has all the decals printed thereon, and the decals are cut along dash lines

indicating the edges of the decals. The sheet 76 can be folded and included in a box or kit 78 (Fig. 11), in a suitable cut-out provided in a cardboard filler or support piece 80 of the box, along with the remaining components of the model.

In Fig. 12, a modified decal sheet 81 of paper having decals for various parts of an airplane outlined thereon is shown. These decals are spaced so as to facilitate cutting from the sheet. For example, a decal for a wing is indicated at 82 and has various indicia thereon indicating ribs 83, numerals 84, insignia 85 and colored portions 86. A decal 87 for a fuselage is also outlined with indicia on its surface representing various elements of the fuselage. A decal 88 for a rudder and a decal 89 for a stabilizer are also outlined. Decals for various miscellaneous parts of the airplane are outlined and indicated at 91, 92 and 93. The sheet may be readily folded in place in a box or kit such as the box 78 shown in Fig. 11.

The idea of the invention can, of course, be carried out to any extent desired, it being mainly important to note that the invention does encompass the idea of substituting decals for the hand-painted surfaces heretofore required on models, with the decals being so designed as to permit them to be super-imposed one upon another, the several decals and the model itself having identifying indicia which facilitates selection of the decals, and which also serve for aligning of superimposed decals one with another.

It is to be understood that this decalcomania may be made of any size and design with a suitable plastic base to transfer and adhere to plastic, wood, metal or other models, and may be of a transfer type of decal. These decalcomanias may be put on the various parts of the models prior to the assembly of the component parts.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

In a construction model of the type sold in disassembled condition for assembly by the purchaser, a plurality of decals each of which bears a representation to be applied to the surface of a model, said decals all having a common identifying means so as to indicate decals which are to be located at a single place upon the model, said identifying means being in the form of numerals, with the model having corresponding numerals on its surface to show the location at which the several decals are to be placed in superposed position thereupon, said identifying numerals being spaced apart on each decal so as to provide spaced guide points to insure proper placement of the several decals in relation to the model and to each other, and other decals proportioned to cover the exposed identifying numerals after assembly, said last-named decals being in the form of opaque pieces colored to match adjacent areas of the model.
